ATTORNEY

UNITED STATES PATENT OFFICE.

LEWIS K. DAVIS, OF NEW YORK, N. Y.

BUILDING CONSTRUCTION.

No. 867,252.

Specification of Letters Patent.

Patented Oct. 1, 1907.

Application filed January 11, 1907. Serial No. 351,894.

To all whom it may concern:

Be it known that I, LEWIS K. DAVIS, a citizen of the United States, and a resident of the city of New York, in the county of New York and State of New York, 5 United States of America, have invented certain new and useful Improvements in Building Construction, of which the following is a specification.

My invention relates to an improvement in systems of building construction and its object is to provide a 10 simple and inexpensive fireproof construction for floors or other structures.

I will describe my invention in the following specification and point out the novel features thereof in claims.

15 Referring to the drawings, Figure 1 is an end elevation of a tile of special design which I have invented. Fig. 2 is a side elevation of the same. Fig. 3 is a sectional elevation of a floor made according to my invention. Fig. 4 is a sectional elevation of a portion of 20 a floor showing a modification of my invention.

Like characters of reference designate corresponding parts in all of the figures.

25 10 designates a tile in the form of a rectangular trough having a flat body portion 11 and side portions 12, 12 which extend vertically from the sides of the body portion 11. The sides are provided with flaring projections 13, 13. These may be in the form of bosses or may be, as shown in the drawings, in the 30 form of parallel ribs extending along the entire length of the tile.

35 14, 14 designate strengthening ribs which extend downward from the flat body portion 11 of the tile. The depth of the tile is added to thereby so that its strength is materially increased without adding 40 greatly to its weight. The tile may be constructed of any suitable material such, for example, as vitrified clay. I prefer to have it salt glazed.

45 In using tiles of the above described form for the construction of a floor a plurality of them are laid side by side as shown in Fig. 3 with intervening spaces between the tiles. The tiles are preferably laid in straight longitudinal rows and if desired the tiles in adjacent rows may be staggered. The bottoms of the 50 intervening spaces between the adjacent rows of tiles may be closed by a board or plank 21. The spaces between the tiles may then be filled with concrete or cement 20 which may be poured into the spaces in a semi-liquid condition. In conjunction with this concrete filling I prefer to use metallic reinforcement 55 such, for example, as steel rods 22, 22 embedded in

the concrete. The concrete is allowed to harden after which the board will be removed. It will then form a portion of the structure itself. The concrete will cling to the sides of the tiles, and because of the flaring shape of the projecting ribs 13, 13, will securely lock 60 and hold the tiles together. The trough portion of the tiles may then be filled with cinders or other suitable material as shown at 23 so as to form a continuous flat surface for the floor.

65 In the modification illustrated in Fig. 4 I have shown a plank 21^a placed under and between adjacent tiles but extending from one of the projecting strengthening ribs 14 on one tile to a similar rib on the adjacent tile. In this case the concrete filler will not only completely fill the intervening spaces between the adjacent tiles 70 but will also extend under a portion of each tile and thereby increase the strength of the structure. I have also shown in this figure a wooden floor of ordinary construction laid on top of the tiles and their filling material.

75 A floor constructed according to this invention has great strength. Its extreme simplicity and ease of setting up give advantages to this construction not found in other structures of this class, and the structure thus formed is light, inexpensive and absolutely fireproof. I have shown this construction as used in forming a floor but it is obviously applicable to other structures.

What I claim is:

1. A floor comprising a plurality of building tiles set 80 in parallel rows with intervening spaces between the rows, each of said tiles comprising a flat body portion, strengthening ribs extending downward from said body portion, side portions extending vertically from the opposite sides of the body portion and flaring projecting ribs upon the outer surface of said side portions; and concrete between the sides of adjacent tiles, said concrete filling the intervening spaces and locking the tiles together.

2. A floor comprising a plurality of building tiles set 85 in parallel rows with intervening spaces between the rows, each of said tiles comprising a flat body portion, strengthening ribs extending downward from said body portion thereby increasing the effective depth of the tile, side portions extending vertically from the opposite sides of the body portion and flaring projecting ribs upon the outer 90 surface of said side portions; concrete between the sides of adjacent tiles, said concrete extending under a portion of each of said tiles between the projecting ribs thereof, and metallic reinforcement embedded in said concrete.

95 In testimony whereof I have signed my name to this 100 specification in the presence of two subscribing witnesses.

LEWIS K. DAVIS.
